CLAIM

The ornamental design for a candle jar, as shown and described.

DESCRIPTION

FIG. 1 is a front, right, top perspective view of a candle jar, showing my design.

FIG. 2 is a rear, left, bottom perspective view of the candle jar.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view thereof, wherein a lid is removed from a jar of the candle jar.

The broken lines in the drawings depict portions of the candle jar that form no part of the claimed design.

1 Claim, 9 Drawing Sheets
